CONTAINER-SEALING MACHINE

James E. Underwood, Phoenixville, Pa., assignor
to The West Company, Philadelphia, Pa., a cor-
poration of Pennsylvania

Application July 11, 1946, Serial No. 682,812

13 Claims. (Cl. 226—87)

1

This invention relates to new and useful improvements in container-sealing machines, and more particularly to machines for sealing cap structures in bottles and other containers holding pharmaceutical preparations such as serums, antitoxins and the like which must be protected from all foreign matter and contamination from any source.

With this in mind one object of the present invention is to provide a machine which is operable substantially automatically to seal the cap structures upon bottles or other containers advancing successively through the machine.

Another object of the invention is to provide a machine of the stated character which is characterized by its flexibility and ready adaptation to cap structures and bottles or containers of different sizes.

Another and highly important object of the present invention is to provide a bottle or container sealing machine of the type set forth which is characterized by the fact that a single adjustment is provided in the machine to effectively and accurately control the extent of movement of the sealing elements of the machine which engage the cap structure and the degree of pressure exerted by said elements against the cap structure to effectively seal the same upon the bottle or other container.

A further object of the invention is to provide a machine having the features and attributes set forth which is of relatively simplified, compact and inexpensive construction; and completely foolproof and efficient in operation and use.

These and other objects of the invention and the various features and details in respect to the construction and operation thereof are hereinafter fully set forth and described with reference to the accompanying drawings, in which:

Fig. 1 is a perspective view of a container sealing machine made according to the present invention, the drive mechanism housing having been removed to better illustrate the same.

Fig. 2 is a view in perspective partially in section showing the construction and arrangement of one type of sealing cap structure which may be employed in a machine of the present invention.

Fig. 3 is a transverse fragmentary sectional view through a bottle or container having a stopper and sealing cap structure in association therewith and showing the relative position of the sealing elements of the machine prior to engagement thereof with the cap structure.

Fig. 4 is a view similar to Fig. 3 showing the

2

manner in which the sealing elements of the machine engage the lower circumferential edge portion of the sealing cap structure and spin or work the same inwardly and beneath the lip portion of the bottle neck so that the sealing cap retains the stopper securely in the bottle or container.

Fig. 5 is an enlarged partial sectional view on line 5—5, Fig. 1.

Fig. 6 is an enlarged fragmentary elevational view partially in section of the head portion of the machine shown in Fig. 1.

Fig. 7 is a sectional view taken on line 7—7, Fig. 6.

Fig. 8 is an enlarged fragmentary elevational view partially in section of the base portion of the machine shown in Fig. 1.

Fig. 9 is a sectional view taken on line 9—9, Fig. 8.

Fig. 10 is a plan view partially in section with reference to line 10—10, Fig. 8.

Fig. 11 is a fragmentary sectional view taken on line 11—11, Fig. 10.

Fig. 12 is a fragmentary sectional view taken on line 12—12, Fig. 11.

Fig. 13 is an enlarged fragmentary sectional view taken on line 13—13, Fig. 5.

Fig. 14 is a fragmentary sectional view of the operating head portion of the machine as viewed with respect to line 14—14, Fig. 13; and

Fig. 15 is a sectional view taken on line 15—15, Fig. 14.

The embodiment of the machine illustrated in the drawings, and hereinafter described with reference thereto, is adapted to secure or seal upon a bottle or container a cap structure of the character shown in Figs. 2, 3 and 4 of the drawings. This cap structure comprises a resilient closure member 1 adapted to fit snugly within the outlet opening 2 of a bottle or other container 3 and having a thin wall 4 adapted to overlie said opening and being pierceable to gain access to the contents of the container. The cap structure includes also an inner retainer element 5 which is adapted to embrace the portion 4 of the closure member 3, a cup-shaped cover cap 6 which is adapted to fit over the retainer element 5, and a second or outer retainer element 7 for the cap 6 which is adapted to fit over the latter, the retainer elements 5 and 7 having portions extending below cap 6 and the projecting lip portion 8 of the bottle and being adapted to be spun or crimped thereunder by a plurality of disc elements of the machine in the manner, for example, illustrated in Figs. 3 and 4 of the drawings.

Referring to Fig. 1 of the drawings, the illus-

trated embodiment of the present machine comprises essentially upper and lower housings 10 and 11, respectively, supported in vertically spaced relation by means of a tubular column 12 for vertical adjustment with respect to each other as more particularly described hereinafter. Journalled in the upper housing portion 10 of the machine by means of bearings 13 and 14 is a shaft 15, the lower end portion of which is received within the upper end portion of a tubular shaft 16 that is rotationally disposed within the aforesaid support column 12. Driving connection between the shaft 15 and the tubular shaft 16 is provided by means of a cross-pin, key or the like 17.

Received coaxially within the lower end portion of the tubular shaft 16 is the upper end portion of a shaft 18 which is journalled in a suitable bearing 19 secured within the lower end of the supporting column 12, and has its lower end portion reduced, as indicated at 20, and journalled in the base 21 of the housing 11 by means of a bearing 22, the said end portion 20 of the shaft 18 extending below the base 21 of said housing 11 and having secured thereon at the underside thereof a suitable gear 23. Driving connection is provided between the tubular shaft 16 and the shaft 18 by means of a key or spline 25 carried by the tubular shaft 16 and slidably engaging elongated longitudinal groove or key-way 26 in the shaft 18 thus permitting the shaft 16 to be moved telescopically with respect to the shaft 18 as the upper housing 10 of the machine and the supporting column 12 may be adjustably positioned vertically with respect to the lower housing 11 of the machine.

Suitably secured upon the upper end portion of the shaft 15 is a pulley 27 which is adapted to be rotationally driven by means of a V-belt 28 from a pulley 29 fixed on the shaft 30 of a suitable source of rotational power such as an electric motor M that may be supported in the relative position shown in Figs. 1 and 5 of the drawings, by means of a bracket 31 suitably supported laterally and rearwardly of the upper housing 10, for example, by means of studs 32.

Referring now more particularly to Figs. 8 and 9 of the drawings, the gear 23 secured upon the lower end of the shaft 18 is meshed with a suitable gear 33 on a shaft 34 journalled in a bracket 35 secured upon the base 21 of the lower housing 11. Also fixed on the shaft 34 is a worm 36 which is meshed with a worm wheel 37 that is fixed on a shaft 38 rotationally mounted in a horizontal position upon the base 21 by means of bearings 39 and 40. Rotationally receiving the reduced portion of the shaft 38 adjacent the bearing 40 is a sleeve 41 which is supported with respect to the shaft 38 by means of sleeve bearings 42 and 43, respectively. Suitably keyed or otherwise fixed to the sleeve 41 is a gear 44 and driving connection to the latter from the shaft 38 is effected through said sleeve 41 by means of a jaw-type clutch, one member 45 of which is slidably keyed to the sleeve 41 and normally urged into engagement with a driving clutch member 46 by means of a spring 47.

Carried by the clutch member 45 is a pin 48 and in order to effect disengagement of the clutch member 45 from the clutch member 46 to break the driving connection from the shaft 38 to the gear 44, a movable cam or lever 49 having the general shape of a bell-crank is provided and pivotally mounted as at 50 by a bracket 51 secured at the underside of the base

21, the arrangement being such that the upper end of the member 49 may be pivoted into and out of the path of the pin 48 carried by the movable clutch member 45. Movement of the cam member 49 as described may be accomplished by a suitable manually-operated control rod 52 or by means of a connecting rod or the like 53 actuated through the medium of a conventional type foot-treadle (not shown).

10 In the present instance the cam member 49 normally is urged into the path of the clutch pin 48 (the dotted line position in Fig. 8) by means of a spring 54 associated with the control rod 52, and it will be apparent that by this 15 construction the cam member 49 operates normally to hold the clutch member 45 disengaged from the other clutch member 46 so that no driving connection exists between the shaft 38 and gear 44. Accordingly, to establish driving 20 connection to the gear 44, the cam lever 49 must first be moved out of the path of the clutch pin 48 to the solid line position shown in Fig. 8 by actuation of the rod 53 through a foot treadle 25 (not shown) or by manual actuation of the control rod 52.

The gear 44 on shaft 38 is meshed with a gear 55 fixed on a shaft 56 which is rotationally supported upon the base 21 parallel to the shaft 38 by means of suitable bearings 57 and 58. 30 Also fixed on the shaft 56 at the opposite end thereof from the gear 55 is a bevel gear 59 which is meshed with a similar bevel gear 60 that is secured on a shaft 61 rotationally supported perpendicular to the shaft 56 by means of suitable bearings 62 and 63.

35 As shown in Fig. 9 of the drawings, the shaft 61 projects through the wall of the housing 11 to a point therebeyond and has fixed on its projecting end a bevel gear 64 which is meshed with a corresponding bevel gear 65 fixed on the lower end of a vertically arranged shaft 66 supported exteriorly of the housing 11 and mechanically connected to an aligned upper shaft 67 by means of a conventional slip clutch 68. Carried at the upper end of the shaft 67 is the actuator member 69 of a Geneva drive mechanism which member 69 carries an upwardly projecting pin 70 (see Figs. 8 and 10) arranged to engage circumferentially spaced slots 71 in the driven member or wheel 72 of said Geneva mechanism. The Geneva wheel 72 is secured to the lower face of a hub member 73 which has secured upon its opposite face a feed plate 74, and the Geneva wheel 72, hub 73 and plate 74 are secured together by means of bolts or the like 75, the entire assembly being rotatably supported above the housing 11 upon an upstanding stud 76. The construction and arrangement of the Geneva mechanism is such that each time the pin 70 of the actuator member 69 moves into engagement with one of the slots 71 of the wheel 72, the latter and the associated feed plate 74 are rotated a predetermined distance, for example in the direction of the arrow in Fig. 10.

65 As best shown in Fig. 10 of the drawing, the feed plate 74 has formed therein a series of openings 77 arranged circumferentially of the plate 74 corresponding to the positions of the slots 71 in the Geneva wheel 72. The openings 70 77 in the feed plate 74 are adapted to receive suitably sized sleeves 77a for bottles or containers to be advanced by said plate 74 into cap-sealing position in the machine. During travel of the bottles or containers with the plate 75 74 through a major portion of the rotational

course thereof, the bottles or containers have their lower ends or bottoms slidably supported upon a plate 78 which circumscribes the hub 73 and is fixedly secured to the top of the housing 11 intermediate the Geneva wheel 72 and the said feed plate 74. As previously stated, a slip clutch 68 is interposed between the shafts 66 and 67 and this is done for safety purposes to prevent damage to the drive mechanism of the machine in the event of jamming in the cap-sealing operation which might prevent movement of the plate 74 in its proper manner to advance succeeding bottles into the cap-sealing position.

In alignment of the particular opening 17 in the feed plate 74 which is disposed in the cap-sealing position, there is formed in the support plate 78 an opening 81 for an elevating mechanism that is adapted to be moved upwardly to engage the underside of the bottle or container in said opening 17 and actuate the same upwardly into position for the cap-sealing operation to be performed thereon. This elevator mechanism comprises a piston-like structure including a head 82 which is adapted to receive a block 82a of predetermined size according to the particular size bottle or container being sealed. Secured to and extending downwardly from the head 82 is a sleeve 83 which carries at its lower end a transverse shaft 84 which mounts a roller 85 that is arranged to ride upon the periphery of a cam 86 suitably keyed or otherwise secured upon the previously described shaft 56, the said roller 85 normally being held in engagement with the periphery of the said cam 86 by means of a spring 87.

Referring now more particularly to Figs. 5, 6 and 7 of the drawings, extending vertically through the upper housing 10 of the machine and arranged coaxially of the opening 81 in the plate 78 through which the bottle or container elevating mechanism operates, is a spindle 90 which has its upper end rotatably supported in a bridge piece 91 which forms a part of a cover or housing 92 which normally encloses the various drive belts and pulleys at the top of the machine. Threaded on the spindle 90 in overlying relation with respect to the bridge piece 91 is a collar 93 whereby the spindle 90 may be secured in the position to which adjusted relative to the bridge piece 91, for example, by means of a set screw or the like 94.

Secured upon the lower end of the spindle 90 is a block 95 which is adapted to engage upon the upper surface of the cap structure of a bottle or container advanced into position beneath by the feed plate 74. In this connection it is to be observed that the vertical position of the spindle 90 is adapted to be adjusted with respect to the supporting bridge piece 91 with reference to the size of the block 83 of the bottle elevating mechanism so that as the latter actuates a bottle or container upwardly through the action of the cam 86 on the shaft 56 the block 95 at the lower end of the spindle 90 will engage the top of the cap upon such bottle or container with sufficient pressure to hold the bottle with its cap thereon relatively firmly against displacement during the sealing operation.

Loosely surrounding the spindle 90 and extending substantially coextensive of the length thereof is a tubular shaft 96 which is supported for rotation circumferentially of the spindle 90 by means of a ball bearing assembly 97 that is supported by the head portion 98 of a guide sleeve 75

which extends an appreciable distance axially about and along the tubular shaft 96, the said head portion 98 of the sleeve 98 being secured against rotation to the upper housing structure 10, for example, by means of a bolt or the like 100. The lower end of the guide sleeve 98 rests upon an annular washer 101 supported upon a shoulder portion 102 formed circumferentially of the shaft 96 and the latter is further rotationally supported within the lower end of the guide sleeve 98 by means of a suitable sleeve bearing or the like 103.

Carried by the lower end of the tubular shaft 96, as indicated at 104, is a spinning head, generally designated H. This head H comprises an upper casing member 105 having a centrally located neck 106 which is threaded onto the tubular shaft 96 and extends upwardly therealong to the underside of the aforesaid shoulder 102 thus serving to index the position of the head H longitudinally of the tubular shaft 96.

In addition to the member 105, the spinning head H comprises a lower casing member 107 of generally annular configuration normally retained in cooperative association with the head member 105, for example, by means of screws or the like 108 whereby said member 105 may be readily removed for replacement or substitution as hereinafter described. Supported in vertical position within the spinning head H are a plurality of studs 109 (see Figs. 13, 14 and 15) which have their upper and lower ends mounted in the head members 105 and 107, respectively, and are arranged in equally spaced relation circumferentially with respect to the common axis of the spindle 90 and the tubular shaft 96 as shown.

Pivotedly mounted upon each of the spindles 109 are brackets 112 arranged for movement about the spindles 109 in the directions indicated by the arrows in Fig. 13. Upon each of the brackets 112, for example, by means of a screw or the like 113, is mounted a roller 114, and also mounted upon each of the brackets 112 is a stud 115 which carries at its lower end a spinning disk or the like 116 arranged immediately below the bracket 112, the said spinning disks 116 normally being biased upwardly against the underside of their brackets 112 by means of a spring 117 which acts between the upper end of the stud 115 and the face of a suitable ball-type thrust bearing 118. The brackets 112, together with their rollers 114 and spinning disks 116, normally are biased in a generally outward direction with respect to the spinning head H by means of suitable springs 119 and recesses 120 are provided in the head member 107 to receive the spinning disk elements 116 in their outer positions. As previously stated, the head member 105 is removable to permit replacement or substitution of the spinning disks 116 as may be required according to differences in size and shape of the cap structures to be sealed.

Constructed and arranged for cooperative engagement with each of the rollers 114 are cam members 121 which extend inwardly of the spinning head H through slots 121a in the top of the head member 105 (see Figs. 5, 13, 14 and 15). These cam members 121 are pivotally mounted upon pins 122 for movement in vertical planes between the relatively spaced parallel arms 123 of a bracket 124 having a central hub portion 125 which embraces the sleeve portion 106 of the spinning head H and is keyed thereto, for example, as indicated at 126, so that the bracket 124 is rotationally connected to the neck portion 106

of the head H but is mounted for axial sliding movement relative thereto.

Movement of the cam members 121 is substantially restricted and radial motion is positively limited by means of stops 127, while upward movement with respect to the rollers 114 is opposed by means of plungers 128 which have their upper ends slidably retained in a plate 129 that is held in position axially with respect to the bracket 124 by means of a collar 130. Associated with each of the plunger 128 is a relatively stiff spring 131 which acts between the plate 129 and the upper face of the plunger 128 normally to cause the latter to maintain the cam members 121 in the position shown in Figs. 5 and 14 of the drawings, it being understood that the illustrated position of the cam members 121 constitutes the normal operating position thereof, and that the pivotal mounting of said cam members and the provision of the spring-biased plungers 128 is made for the purpose of providing a relative small amount of outward give to the cam member 121 to compensate for slight variations in the size and configuration of the caps and neck portions of the bottles or containers being sealed.

The tubular shaft 96, together with the head H and the brackets 112, are rotationally driven at a predetermined speed by means of a pulley 140 secured upon said shaft 96 adjacent the upper end thereof. The pulley 140 in turn is driven by means of a V-belt 141 from a pulley 142 fixed on the drive shaft 15 previously described, the latter being driven by the motor M through pulley 29, belt 28 and the pulley 27.

Movement of the bracket 124 together with its cams 121 axially with respect to the shaft 96 and the head H to actuate the rollers 114, their brackets 112 and spinning disks 116 into operative engagement with the cap structure of the bottle or container (see Figs. 3 and 4) is effected by means of a rocker 150 having relatively spaced arm portions 151 carrying rollers 152 which ride within a grooved collar 153 that is threadably or otherwise secured upon the upper end portion of the cam carrying bracket 124. As shown in Fig. 7, the rocker arm 150 is secured upon a rock shaft 155 which is supported transversely within the housing 10, and the construction and arrangement is such that when the shaft 155 is rocked or rotated, the rocker 150 will be actuated in a manner to cause the roller 152 carried at the free ends of its arm portions 151 to actuate the collar 153 and the bracket 124, together with its cam members 121, axially downward relative to the tubular shaft 96, the head assembly H and the relatively stationary cap holding spindle 90.

As illustrated in Figs. 1, 6 and 7, the rock shaft 155 has one end thereof projecting outwardly of the housing 10 and keyed to this projecting end of the rock shaft 155 is one end of an arm 160 which has its free end adjustably connected by means of a threaded member 161 to another arm 162. This other arm 162 has one end thereof pivotally mounted with respect to the rock shaft 155 and the lever 160, and the free end of said arm 162 carries a roller 163 which contacts the periphery of a cam 164 under the influence or urging of a suitable spring 165. The cam 164 is secured upon a shaft 166 which extends inwardly of the machine and has secured on its inner end a worm wheel 167 that is meshed with a worm 168 secured upon the aforesaid drive shaft 15.

By this construction it will be apparent that as the cam 164 is rotationally driven by its shaft

166, the arm 162 will be periodically actuated into the position shown in Fig. 6 of the drawings and this pivotal or oscillating movement of said arm 162 will operate through the connection 161 to actuate the lever 160 thereby causing the rock shaft 155 to be actuated with resulting vertical reciprocal movement of the bracket 124 and its cam members 121 in the manner set forth above.

A particular feature of the machine of the present invention resides in the construction and arrangement of the arms 160 and 162 and the adjustable connection provided therebetween by the screw member 161. As previously described, the arm 160 is keyed to the rock shaft 155 while the arm 162 is rotatably mounted with respect to both the arm 160 and shaft 155, the arm 162 being actuated by means of the cam 164 and in turn actuating the shaft arm 160 through the said connection provided by the threaded member 161. It will be apparent that adjustment of the member 161 will operate to position the arm 160 in closer relation to, or further away from, the arm 162, as the case may be, depending upon the direction in which the member 161 is rotated.

Thus, for example, if the member 161 is adjusted to move the member 160 in counterclockwise direction to a position in closer proximity to the arm 162 than that shown in Fig. 6, this change in position of the arm 162 will cause the position of the shaft 155 and rocker 150 to be correspondingly changed in a counterclockwise direction so that the initial setting or inoperative position of the bracket 124 and its cam members 121, vertically with respect to the head H, will be below that shown in said Fig. 6. Conversely, adjustment of the member 161 to move the arm 160 in the clockwise direction to a position further removed from the arm 162, it will be apparent that the initial setting or inoperative position of the bracket 124 and cams 121 will be above that illustrated in Fig. 6 of the drawings.

In this manner, merely by adjustment of the single threaded member 161, the initial setting or position of the bracket 124 and cams 121 vertically with respect to the head H may be predeterminedly fixed to thereby regulate and control the extent of movement of the spinning discs 116 with respect to the bottle cap structure as well as the pressure exerted thereby upon the cap structure when spinning the lower edge thereof beneath the projecting lip of the bottle or container, it being apparent that while the extent of the movement of arm 160 and shaft 155 is the same whatever the setting of the member 161, by changing the position from which movement of the bracket 124 takes place or commences, the movement and pressure of the spinning disks with respect to any particular bottle or container and cap structure may be regulated and controlled as required or desired.

As previously stated, provision is made for vertical adjustment of the housing 10 relative to the lower housing 11 and, in the illustrated embodiment of the invention, this is accomplished by providing a rack 170 (see Figs. 10, 11 and 12) which is mounted exteriorly lengthwise of the column 12. Meshed with the rack 170 is a pinion 171 that is mounted within the upper part of the lower housing 11 (see Fig. 1) upon a shaft 173. The shaft 173 has fixed thereon a worm wheel 174 with which is meshed a worm 175 that is secured on a shaft 176. The shaft 176 is adapted to be actuated manually to raise and lower the column 12 and upper housing 10 as required by means of a crank 177, and the column 12 may

be locked in the position to which adjusted, for example, by means of a bolt 178 that may be tightened to clamp blocks 179 and 180 against the column 12 as shown in Fig. 12 of the drawings.

In operation of the machine, the motor M is started to rotationally drive the shaft 15 which in turn drives the shaft 38 through the shafts 16 and 18, and the clutch member 45 is held disengaged with respect to the clutch member 46 by the cam arm 49 so that no drive is established from the shaft 38 to the shaft 56. Also driven from the shaft 15 is the tubular shaft 96 which carries at its lower end the spinning head H. In addition to the shafts 38 and 96, there is also driven from the shaft 15 the shaft 168 which carries the cam 164 that operates to effect reciprocal movement of the bracket 124 and its cams 121 longitudinally of the tubular shaft 96 in the manner previously described herein.

With the several mechanisms of the machine in operation as described, bottles or containers 3 with stoppers 1 and cap structures assembled therein and thereon in the relation shown in Figs. 3 and 4 of the drawings are positioned in successive openings 71 of the feed plate 74. The control bar 52 or foot treadle (not shown) may now be actuated to move the cam arm 49 from the dotted line position in Fig. 8 to the solid line position shown therein to thereby cause the clutch member 45 to engage the clutch member 46 and establish driving connection from the shaft 38 through the shafts 56, 61, 66 and slip clutch 68 to the shaft 67 thus driving the Geneva mechanism to advance the feed plate 74 in a step-by-step manner to successively advance the bottles or containers into the cap-sealing position of the machine in coaxial alignment with the holding spindle 90 and the spinning head H.

As a container or bottle 3 with the stopper 1 and cap structure thereon is moved into the sealing position by the feed plate 74 as described, the cam 86 on the shaft 56 operates through the follower 85 to actuate upwardly the elevator mechanism 83 which is projected through the opening 81 of support plate 78 to engage the underside of the bottle or container 3 and actuate it upwardly to place the top of the cap structure thereon firmly into abutting relation against the underside of the holding block 95 fixed on the lower end of the spindle 90.

The height of the block 82a of the elevator mechanism is selected according to the height of the particular bottle or container 3 to be sealed in each particular instance, and the vertical position of the holding spindle 90 is predeterminedly fixed by adjustment of collar 93 so that the block 95 at the lower end of said spindle will engage the top of the cap structure on the bottle or container sealing position with sufficient pressure to hold the latter against displacement during the sealing operation.

As the bottle or container 3 is brought into abutting relation against the underside of the holding block 95 by means of the elevator mechanism as described, the cam 164 operating through the arms 162, 160 and connection 161 will cause the shaft 155 to rock the arm 150 thereby causing the rollers 152 of the latter to actuate the bracket 124 axially downward with respect to the rotating shaft 96 and spinning head H and in turn cause the cams 121 carried by said bracket 124 to move the spinning disk elements 116 inwardly into engagement with the lower edge portion of the cap structure to thereby spin or

crimp the same under the lip 8 of the bottle or container 3 as described in detail previously herein.

As operation of the machine continues the bracket 124 and its cams 121 retract and the elevator mechanism moves downwardly thereby returning the now sealed bottle or container 3 to its normal position in the feed plate 74 and resting upon support 78. Feed plate 74 thereupon is rotated through an additional step by the Geneva mechanism to move the sealed bottle or container 3 from the sealing position of the machine and to place the succeeding unsealed bottle in position to be sealed in the manner herein described. As the sealed containers move away from the sealing position they ultimately drop by gravity through the openings 71 in the feed plate 74 onto an inclined trough or chute arranged, for example, as shown in Fig. 1 of the drawings.

In any operation of a machine made according to the present invention it is to be understood that preparatory to such operation the threaded member 161 interconnecting the arms 160 and 162 will be adjusted in the manner previously described in detail herein to provide the necessary movement and pressure of the spinning disk elements 116 to perform the required sealing operation upon the particular cap structure employed. For this purpose, and in order to effect adjustment of the threaded member 161 with extreme exactness, the machine may be manually actuated apart from the motor M, for example, by operating the machine through a hand wrench applied to the projecting upper end 15a of the drive shaft 15 which may be exposed by depressing the cap 181 against the action of its spring 182.

From the foregoing it will be seen that the present invention provides a novel bottle or container sealing machine which is substantially automatic and is characterized by its flexibility and ready adaptation to cap structures and bottles or containers of various sizes. The invention also provides the very important feature of a bottle or container sealing machine of the type described which is characterized by the unique fact that a very easy and quickly made single adjustment is provided to effectively and accurately control the extent of movement of the sealing elements of the machine with respect to the cap structure to be sealed and the degree of pressure exerted by said sealing elements against the cap structure to effectively seal the same upon the bottle or container. The invention further provides a machine having the features and attributes set forth which is of relatively simplified, compact and inexpensive construction and completely foolproof and efficient in operation and use.

While a particular embodiment of the present invention has been illustrated and described herein, it is not intended that the invention be limited to such disclosure and changes and modifications may be made therein and thereto within the scope of the claims.

I claim:

1. In a container sealing machine having a rotatable head carrying a plurality of spinning elements mounted for movement into rolling engagement with the cap on a container, a member reciprocable relative to the head from an inoperative position and operable to effect engagement of said spinning elements with the cap to seal the same on the container, a rocker engag-

ing said member to actuate the same relative to said head, a shaft mounting said rocker, a first arm fixed on said shaft, a second arm on said shaft mounted for rotation relative to said shaft and said first arm, means to impart an oscillatory movement to said second arm, and adjustable means interconnecting said first and second arms operable to vary the relative positions thereof with respect to each other rotationally of the shaft and thereby predeterminedly position said shaft and fix the inoperative position of said member from which movement thereof relative to the head takes place.

2. In a container sealing machine having a rotatable spinning head carrying a plurality of spinning elements mounted for movement into rolling engagement with the cap on a container, a member reciprocable relative to the head from an inoperative position and operable to effect engagement of said spinning element with the cap to seal the same on the container, a rocker engaging said member to actuate the same relative to said head, a shaft mounting said rocker and arranged to be rotated through a selected number of degrees from an initial set position, a first arm fixed on said shaft, a second arm mounted for rotation coaxially of said shaft and relative to said first arm, means to impart an oscillatory movement to said second arm, and threaded means adjustably interconnecting said first and second arms operable to vary the relative positions thereof rotationally with respect to each other and thereby predeterminedly position said shaft and fix the inoperative position of said member from which movement thereof relative to the head takes place.

3. In a container sealing machine of the character described comprising a rotatable head and means to rotationally drive said head, a plurality of arms pivotally carried by the head for movement in a common plane normal to the rotational axis of the head toward and away from a container positioned coaxially thereof, a spinning element on each arm arranged for rolling engagement with a cap on the container, a member reciprocable coaxially of the head from an inoperative position, and a plurality of resiliently biased cam elements pivotally carried by said member and arranged respectively to actuate said arms and cause said spinning elements to engage the cap on the container.

4. In a container sealing machine of the character described comprising a rotatable head and means to rotationally drive said head, a plurality of arms pivotally carried by the head for movement in a plane perpendicular to the rotational axis of the head toward and away from a container positioned coaxially thereof, springs means normally biasing said arms outwardly away from the header, a spinning element on each arm arranged for rolling engagement with a cap on the container, a member reciprocable coaxially of the head from an inoperative position, a plurality of cam elements pivotally carried by said member and arranged respectively to engage said arms and cause said spinning elements to engage the cap of the container, and spring means independently opposing pivotal movement of each cam in the direction to which urged by engagement of said arms.

5. In a container sealing machine of the character described comprising a rotatable head and means to rotationally drive said head, a plurality of spindles secured in said head at equally spaced intervals circumferentially of the rotational axis

of the head and parallel thereto, an arm pivotally mounted on each spindle for movement in a plane perpendicular to the rotational axis of the head toward and away from a container positioned coaxially thereof, spring means normally biasing said arms outwardly away from the container, a spinning element on each arm arranged for rolling engagement with a cap on the container, a bracket reciprocable coaxially of the head from an inoperative position, and a plurality of resiliently biased cam elements pivotally carried by said bracket and arranged respectively to actuate said arms and cause said spinning elements to engage the cap of the container.

6. In a container sealing machine of the character described comprising a rotatable head and means to rotationally drive said head, a plurality of arms pivotally carried by the head for movement in a plane perpendicular to the rotational axis of the head toward and away from a container positioned coaxially thereof, spring means normally biasing said arms outwardly away from the container, a spinning element on each arm arranged for rolling engagement with a cap on the container, a roller carried by each of said arms, a bracket reciprocable coaxially of the head from an inoperative position, a plurality of cam elements pivotally carried by said bracket and arranged respectively to engage the rollers on said arms and cause said spinning elements to engage the cap of the container, and spring means independently opposing pivotal movement of each cam in the direction to which urged by engagement of said rollers.

7. In a container sealing machine of the character described comprising a rotatable head and means to rotationally drive said head, a plurality of spindles secured in said head at equally spaced intervals circumferentially of the rotational axis of the head and parallel thereto, an arm pivotally mounted on each spindle for movement in a plane perpendicular to the rotational axis of the head toward and away from a container positioned coaxially thereof, spring means normally biasing said arms outwardly away from the container, a spinning element on each arm arranged for rolling engagement with a cap on the container, a roller carried by each of said arms, a bracket reciprocable coaxially of the head from an inoperative position, a plurality of cam elements pivotally carried by said bracket and arranged respectively to extend inwardly of the head and engage the rollers on said arms and cause said spinning elements to engage the cap of the container, and spring means individually opposing pivotal movement of each cam in the direction to which urged by engagement of said rollers.

8. In a container sealing machine of the character described comprising a rotatable head and means to rotationally drive said head, a plurality of arms pivotally carried by the head for movement in a plane perpendicular to the rotational axis of the head toward and away from a container positioned coaxially thereof, spring means normally biasing said arms outwardly away from the container, a stud carried by each arm and arranged with its axis parallel to the axis of the head, a spinning element on each stud arranged below said arm for rolling engagement with a cap on the container, a roller carried by each of said arms, a bracket reciprocable coaxially of the head from an inoperative position, a plurality of cam elements pivotally carried by said bracket and arranged respectively to extend inwardly of the

head and engage the rollers on said arms and cause said spinning elements to engage the cap of the container, and spring means opposing pivotal movement of each cam in the direction to which urged by engagement of said rollers.

9. In a container sealing machine of the character described comprising a rotatable head and means to rotationally drive said head, a plurality of spindles secured in said head at equally spaced intervals circumferentially of the rotational axis of the head and parallel thereto, an arm pivotally mounted on each spindle for movement in a plane perpendicular to the rotational axis of the head toward and away from a container positioned coaxially thereof, spring means normally biasing said arms outwardly away from the header, a spinning element on each arm arranged for rolling engagement with a cap on the container, a bracket reciprocable coaxially of the head from an inoperative position, a plurality of resiliently biased cam elements pivotally carried by said bracket and arranged respectively to extend inwardly of the head and engage the rollers on said arms and cause said spinning elements to engage the cap on the container, spring means opposing pivotal movement of each cam in the direction to which urged by engagement of said rollers, and means positively limiting movement of each cam in the opposite direction.

10. In a container sealing machine comprising a rotatable head carrying a plurality of spinning elements actuatable into engagement with the cap on a container, a member reciprocable coaxially toward and away from the head from a predetermined relatively spaced position, a plurality of cam elements pivotally carried by said member and arranged respectively to effect actuation of said spinning elements into engagement with the cap on the container upon reciprocation of said member toward said head, spring means normally biasing each cam individually in one direction and yielding to movement of each cam in the opposite direction to compensate for slight variation in the size and configuration of the caps and containers.

11. In a container sealing machine comprising a rotatable head carrying a plurality of spinning elements actuatable into engagement with the cap on a container, a member reciprocable coaxially toward and away from the head from a predetermined relatively spaced position, a plurality of cam elements pivotally carried by said member and arranged respectively for movement in vertical planes radially disposed with respect to said head axis to effect actuation of said spinning elements into engagement with the cap on the container upon reciprocation of said member toward said head, and spring means individually opposing pivotal movement of each cam in the radially outward direction while yielding to movement of each cam in that direction to compensate for

slight variations in the size and configuration of the caps and containers.

12. In a container sealing machine of the character described comprising a rotatable head and means to rotationally drive said head, a plurality of arms pivotally carried by the head for movement in a plane perpendicular to the rotational axis of the head toward and away from a container positioned coaxially thereof, spring means normally biasing said arms outwardly away from the header, a spinning element on each arm arranged for rolling engagement with a cap on the container, a bracket reciprocable coaxially of the head from an inoperative position, a plurality of resiliently biased cam elements pivotally carried by said bracket and arranged respectively to actuate said arms and cause said spinning elements to engage the cap of the container, and mechanism operable to reciprocate said bracket including means to predeterminedly fix the inoperative position of said bracket from which movement thereof relative to the head takes place.

13. In a container sealing machine of the character described comprising a rotatable head and means to rotationally drive said head, a plurality of arms pivotally carried by the head for movement in a plane perpendicular to the rotational axis of the head toward and away from a container positioned coaxially thereof, spring means normally biasing said arms outwardly away from the header, a spinning element on each arm arranged for rolling engagement with a cap on the container, a bracket reciprocable coaxially of the head from an inoperative position, a plurality of cam elements pivotally carried by said bracket and arranged respectively to actuate said arms and cause said spinning elements to engage the cap of the container, spring means individually opposing pivotal movement of each cam in the direction to which urged by engagement of said arms, and mechanism operable to reciprocate said bracket including means to predeterminedly fix the inoperative position of said bracket from which movement thereof relative to the head takes place.

JAMES E. UNDERWOOD.
